COMBINED BALL HOLDER, AND UPPER PLATE
FOR A TENNIS RACKET PRESS

Richard J. Gould, Vassar, Mich.

Application April 22, 1957, Serial No. 45,827

Term of patent 14 years

(Cl. D34—5)

FIG. 1

FIG. 2

Fig. 1 is a perspective view showing a combined ball holder, and upper plate for a tennis racket press embodying my new design.

Fig. 2 is a top plan view thereof.

The broken line showing of the tennis racket and the balance of the press are for purposes of illustration only.

I claim:

The ornamental design for a combined ball holder, and upper plate for a tennis racket press, substantially as shown and described.
